UNITED STATES PATENT OFFICE

112,119

DESIGN FOR A RURAL MAIL BOX SUPPORT

Ola Whitfield Isle, Decatur, Ill.

Application November 27, 1939, Serial No. 88,509

Term of patent 14 years

To all whom it may concern:

Be it known that I, Ola W. Isle, a citizen of the United States of America, residing at Decatur, in the county of Macon and State of Illinois, have invented a new, original, and ornamental Design for a Rural Mail Box Support, of which the following is a specification, reference being had to the accompanying drawing, forming a part hereof.

I claim:

The ornamental design for a rural mail box support, as shown.

OLA WHITFIELD ISLE,
